DESIGN FOR A SIGN OR THE LIKE

Charles P. Partridge, Richmond, Calif.

Application May 4, 1943, Serial No. 110,111

Term of patent 14 years

(Cl. D1—12)

To all whom it may concern:

Be it known that I, Charles P. Partridge, a citizen of the United States, residing at 50 Washington Avenue, Richmond, in the county of Contra Costa and State of California, have invented a new, original, and ornamental Design for a Sign or the like, of which the following is a specification, reference being had to the accompanying drawing, forming part thereof.

In the drawing, the figure is a front elevational view of a sign or the like showing my new design.

The article shown is of conventional thickness and no parts thereof project from the surface.

I claim:

The ornamental design for a sign or the like, as shown and described.

CHARLES P. PARTRIDGE.
